Patented June 30, 1964

198,531

HOUSING FOR SONIC RECORDING AND REPRODUCING CONTROL SYSTEM

Ross H. Beville, Bethesda, Md.
(8800 Brookeville Road, Silver Spring, Md.)

Filed May 6, 1963, Ser. No. 74,776

Term of patent 14 years

(Cl. D26—14)

FIG. 1

FIG. 2

FIG. 1 is a left side, top and front perspective view of a housing for sonic recording and reproducing control system, showing our new design; and

FIG. 2 is a top plan view thereof.

The side not shown is similar to the side shown, and the rear is substantially a conventional flat unornamented surface.

I claim:

The ornamental design for a housing for sonic recording and reproducing control system, as shown and as described.
